UNITED STATES PATENT OFFICE.

ROBERT P. McCURDY, OF PITTSBURGH, PENNSYLVANIA, AND FREDERICK W. HOCHSTETTER, OF DAYTON, OHIO, ASSIGNEES, BY MESNE ASSIGNMENTS, TO SAID HOCHSTETTER.

NONGLARE ELECTRIC LAMP FOR HEADLIGHTS.

Application filed May 23, 1924. Serial No. 715,406.

The object of this invention is to provide an electric filament bulb lamp with an interior shield or light-filter which will prevent the projection of blinding rays into the eyes of a person positioned in front of the headlight in which the bulb is placed, and the special object of the invention is to so construct the non-glare shield that it shall be enclosed within the lamp-globe, where it will be out of the way and will be protected from breaking in handling, as more fully hereinafter set forth.

In the drawing—

Fig. 1 is a front view of our improved lamp;

Fig. 2 is a side elevation thereof;

Figs. 3 and 4 are similar views showing a modified arrangement of the screen or shield.

Referring to Figs. 1 and 2, the shield 5 is shown as being made of glass formed integral with the usual filament-base 6. The shield is molded on the base at the same time the filament is molded or cast therein. The shield is supported on a laterally-extending offset 7, and it lies in a vertical position in front of the filament. The shield is tinted to render it ray-filtering. The shield has sufficient dimensions to cover the filament when the same is viewed from a point in front of the headlight. The shield must, of course, be suf-

ficiently narrow to be passed into the bulb 30 through the neck thereof at the same time the filament-base is inserted. The filament-base is sealed within the neck of the bulb in the usual manner.

In the construction shown in Figs. 3 and 4, 35 the shield is shown as a separate element cemented in a recess in the lateral offset 7. This shield is shown as being constructed of a very fine wire mesh, sometimes referred to as a mosaic screen. This fine wire mesh produces 40 approximately the same translucent effect of etched or tinted glass, and therefore serves to filter out or block off the blinding rays of light.

What we claim as new is:

An electric filament lamp for use in headlights having the usual central filament projecting from the filament-base, and a light-filtering non-glare shield composed of a piece of ray filtering material supported on a 50 forwardly-projecting offset from the top of said filament-base in front of said filament, for the purpose set forth.

In testimony whereof we hereunto affix our signatures this 22nd day of May, 1924.

ROBERT P. McCURDY.
FREDERICK W. HOCHSTETTER.
